UNITED STATES PATENT OFFICE

WILLIAM AAB, OF NEW ULM, MINNESOTA

REAMING TOOL FOR CONNECTING RODS

Application filed September 23, 1926. Serial No. 137,829.

This invention relates to a tool constructed and arranged to facilitate the reaming operations in the bores of connecting rod bushings, or similar articles. Such connecting rods are now used in large numbers in automobiles. It is frequently necessary to renew the bushing in the connecting rods which embraces the wrist pin and ream the same. Difficulty has been experienced in 10 properly finishing the bore of the bushing especially by inexperienced workmen, and the bore is frequently made larger at its ends, owing to the fact that the reamer is tilted and is not passed through the bore 15 co-axially therewith.

It is an object of this invention, therefore, to provide means constructed and arranged to properly guide the reamer and center the same while the bore of the bushing in the 20 connecting rod is being finished.

It is a further object of the invention to provide means for centering and guiding the reamer comprising a member adapted to engage and be clamped to the connecting 25 rod having another member attached thereto and relatively movable thereto carrying a centering means for the reamer, which latter member is adapted to be properly adjusted and held in adjusted centering position.

It is still another object of the invention to provide a member engaging and clamping the connecting rod including clamping jaws and having a flat surface at one end 35 engaged by a flat plate which is longitudinally and laterally movable on said member and adapted to receive a centering means for the reamer, together with means for holding said plate in properly adjusted position.

These and other objects and advantages of the invention will be fully set forth in the following description made in connection with the accompanying drawings in which like characters refer to the different parts throughout the different views, and in which,

Fig. 1 is a plan view of the device showing a connecting rod and reamer in connection therewith, together with a vise in which 50 the connecting rod is held;

Fig. 2 is a vertical section taken on the line 2—2 of Fig. 1, as indicated by the arrows;

Fig. 3 is a vertical section taken on the line 3—3 of Fig. 2, as indicated by the arrows;

Fig. 4 is a vertical section taken on the line 4—4 of Fig. 2, as indicated by the arrows;

Fig. 5 is a plan detail view of one of the 60 parts used;

Fig. 6 is a plan detail view of another of the parts of the device; and

Fig. 7 is a partial view similar to Fig. 3, showing the parts in locating position.

Referring to the drawings, a connecting rod 10 is shown in Fig. 1, such as now commonly used on automobile or internal combustion engines. In Fig. 3 the connecting rod 10 is shown as clamped between the jaws 11 and 12 of a vise, the connecting rod being so held when the reaming operation is performed. The connecting rod 10 has a hub 10^a at one end which is bored and reamed to embrace the usual piston pin in the piston of the engine cylinder.

In accordance with the present invention, a tool is provided comprising a member 15 preferably formed as a casting, which member has spaced jaw portions 15^a at one end, 80 each of which has one flat jaw surface 15^b disposed substantially at right angles to the longitudinal axis of the member 15 and having another jaw surface 15^c disposed at an acute angle to the surface 15^b. The member 15 has, at its end opposite the jaw 15^a, a flat surface 15^d formed on a pair of lugs 15^e. The central portion of the member 15 is formed as a web having thickened portions 15^f at the sides thereof, as clearly 85 shown in Fig. 3. The member 15 also has projecting from one side thereof, spaced lugs 15^g between which lugs is pivoted a member 16 by means of the pivot 16^c shown as riveted in place. The member 16 is formed 90 as a jaw at its outer end, which end alines laterally with the jaw portions 15^a, which jaw has a surface 16^a which, when in clamping position, extends at an angle slightly less than a right angle to the surface 15^b, as

shown in Fig. 2. The member 16 has pivoted thereto, intermediate its ends, a small U-shaped yoke member 17 having secured in the bright portion thereof, one end of a screw 18, which jaw extends toward the member 15 and extends through an aperture 15^b in the web of member 15. The free end of the jaw is engaged in a threaded bore in the end of a clamping member 19 illustrated as a cylindrical rod having a handle rod 19^a extending at right angles therethrough adjacent its outer end. A plate 20 is provided illustrated as having flat surfaces and being of substantially uniform thickness, which plate has a slot 20^a extending longitudinally from one end and terminating in a circular enlargement 20^b. Said plate has an offset circular portion at one end having a circular aperture 20^c extending therethrough. A pair of headed screws 21 extend through the plate 20 and the slot 20^a and are threaded into the lugs 15^e, washers 22 being disposed beneath the heads of screws 21. A compression spring 23 is disposed between the members 15 and 16 between lugs 15^e and yoke 17, the ends of which embrace small pins or projections 16^b and 15ⁱ, respectively, which project from members 15 and 16, respectively, these pins or projections acting to hold said spring in place. A centering member or cone 24 is provided which, as shown in Figs. 3 and 7, comprises a member having oppositely extending frusto-conical end portions having therebetween, a cylindrical portion 24^a of enlarged diameter having its periphery knurled. The member 24 is divided along a diametral plane and hinged at one side so that it may be readily opened and closed. An adjustable reamer 25 is shown, and while any adjustable reamer may be used, in the embodiment of the invention illustrated, a reamer is shown having a threaded cylindrical end portion 25^a and an intermediate portion having longitudinally extending grooves 25^b therein. The grooves 25^b are adapted to receive reamer blades 25^c and these blades may be moved longitudinally to increase or decrease the diameter of a circle engaging their outer surfaces by being moved longitudinally in the grooves 25^b by the collars 25^d which receive the ends of said blades and are moved longitudinally by the nuts 25^e. The bottoms of the grooves 25^b are inclined to the axis of the reamer so that the blades are cammed outwardly by said grooves, it being understood that the reamer is also threaded throughout the portion occupied by the grooves 25^b. When the bore of the connecting rod hub is to be reamed, the connecting rod will be placed in and clamped in some holding means, such as the jaws 11 and 12 of a vise, as illustrated. The tool of the present invention will then be engaged with and

clamped on the connecting rod, as shown in Figs. 1 and 2. It will be seen that, owing to this position of the jaw surfaces 15 and 16^a, the connecting rod 10 will be clamped between said surfaces and forced against the surface 15^b. The surface 15^a has just enough inclination or draw to cause the connecting rod 10 to be properly clamped and prevents any tilting of the same away from the jaw surface 15^b. The connecting rod is thus held with the axis of the hub 10^a and the bore therein substantially parallel with the longitudinal central axis of the member 15. The reamer 25 is now placed in position, as shown in Fig. 7, with the blades 25^c substantially longitudinally centered in the hub 10^a, said blades being adjusted so that the reamer fits snugly in the bore of hub 10^a. The reamer, at this time, extends through the aperture 20^c in plate 20. The centering cone or shell 24 is now closed about the threaded end of the reamer 25 at the outer side of the plate 20 and is then screwed on the reamer toward the hub 10^a. The cone now centers the aperture 20^c so that its center is co-axial with the reamer. When the plate 20 is thus accurately centered with the reamer, the screws 21 are tightened to hold the plate firmly in position on member 15. It will be seen that the plate 20 can move longitudinally on member 15 and can also be swung laterally about the screws 21 nearest the end of the plate, the aperture 20^c permitting this lateral swinging movement. When the plate is thus centered the reamer is withdrawn from the bore of hub 10^a and the reamer is then adjusted to the proper size for reaming out said bore. The reamer is then inserted into the bore, as shown in Fig. 1, the threaded end engaging in the cone 24. The reamer is now turned, as usual, and is drawn or fed through the bore in the hub 10^a by the threads thereon engaging the threaded interior of the cone 24. The reamer is thus guided in perfect and accurate alignment with its axis co-axial with the axis of the bore and of the centering cone 24 so that there is no chance for the reamer to tilt or move into position with its axis inclined to the axis of the bore. A perfect cylindrical bore is thus made in the hub 10^a. When the tool is to be released from the connecting rod the handle 20 and member 19 will be slightly turned and the spring 23 will force the member 16 away from member 15 so that the jaws on members 15 and 16 will only have to be separated slightly to release the rod. It will be understood that different plates 20 will be used with different connecting rods and with different sized bores in the bushings thereof. The plate 20 is offset at one end so that, if desired or necessary, a greater distance may be had between the end of the hub 10^a of the connecting rod and the plate, thus allowing plenty

of room for the reamer to move through the bushing or hub 10^a without engaging said plate or the centering cone 24. This greater distance is obtained by reversing said plate.

5 From the above description it is seen that applicant has provided a very simple, convenient and highly efficient device for use in reaming out the bushings in connecting rod hubs. The tool is simple in construction and 10 easily and quickly positioned. The connecting rods can thus be reamed by workmen who are not experienced machinists and a perfect job will be done. The device has been amply demonstrated in actual practice 15 and found to be very successful and efficient.

It will, of course, be understood that various changes may be made in the form, details, arrangement and proportions of the parts without departing from the scope of 20 applicant's invention which, generally stated, consists of the parts and combinations of parts disclosed and defined in the appended claims.

What is claimed is:

25 1. A device for use in reaming the bores of bushings in connecting rods or similar devices having in combination, means for engaging and clamping a connecting rod comprising a member having a jaw at one 30 end with one surface extending substantially normal to the longitudinal axis of said member and another surface inclined at an acute angle to said surface, a member pivoted to said member having a jaw at one end with a 35 surface making an angle of slightly less than ninety degrees with said first mentioned surface, means for moving said jaws to clamp a connecting rod therebetween, said member having a flat surface at its end opposite said 40 jaw, spaced headed screws threaded into said member, a plate engaging said flat surface disposed under the heads of said screws and having a slot therein embracing said screws with an enlargement at one end about one of 45 said screws, said plate having an opening therein at one side of said member, and a centering means positioned in said opening adapted to receive a reamer to position said plate with said opening co-axially aligned 50 with the bore of said bushing, said centering means being adapted to guide and feed said reamer.

2. The structure set forth in claim 1, means for moving said first two members together to clamp said connecting rod, and a spring for moving said members apart.

3. A device for reaming the bushings of connecting rods or similar devices having in combination, a member having an angular 60 jaw at one end, a jaw pivoted to said member and cooperating with said angular jaw to clamp the shank of a connecting rod, said member having a flat surface at its opposite end, a plate movable over said surface, means 65 for clamping said plate in fixed position on

said surface, said plate having an aperture therethrough adapted to be axially aligned with the bore in said connecting rod and conical centering means disposed in said opening and internally threaded to propel a reamer through said bore upon rotation of said reamer. 70

4. A device for reaming the bushings of connecting rods or similar devices having in combination, a member having a fixed jaw at one end, a jaw member pivoted to said member and adapted to cooperate therewith to clamp the shank of a connecting rod, one of said jaws having a flat surface against which the wide side of the connecting rod shank engages, said member having lugs at its opposite end having flat surfaces, screws threaded into said lugs, a plate clamped against said surfaces by said screws and having a slot embracing said screws whereby said plate is longitudinally and laterally movable on said flat surfaces said plate having an aperture in one end, a centering member receivable in said aperture and being internally threaded to engage the threaded shank of a reamer whereby said plate can have the aperture therein axially aligned with the aperture in the bore of said connecting rod by loosely inserting the reamer in said bore and having it engaged by said centering means, said centering means acting to propel said reamer upon rotation of the latter. 80

5. A device for reaming the bushings of connecting rods or similar devices having in combination, a member having a fixed jaw at one end, said jaw having one surface at right angles to its longitudinal axis and having another surface extending at an acute angle thereto, a movable jaw member pivoted to said member and adapted to cooperate with said jaws to clamp the shank of a connecting rod, means for moving said movable jaw member toward said member, said member having at its opposite end a flat surface parallel to the first mentioned surface of said fixed jaw, a plate slidable over said flat surface, means for clamping said plate in fixed position on said surface, said plate having an aperture therethrough, a centering means receivable in said aperture automatically centerable therein and internally threaded to receive the threaded shank of a reamer which may extend through the bore of said connecting rod, the aperture in said plate thus being axially aligned with said bore. 105

6. A device for reaming the bushings of connecting rods or similar devices having in combination, a member having a fixed jaw at one end, a second jaw pivotally connected to said member, one of said jaws having surfaces making an acute angle with each other, means for moving said jaws together to clamp the shank of a connecting rod there- 110 120 125 130

- between, said member having a surface at its opposite end, a member movable in engagement with said surface longitudinally and laterally of said connecting rod, said member having an aperture therein adapted to be axially aligned with the bore of said connecting rod, a centering member received in said aperture and automatically centerable therein, said centering member being internally threaded to receive the threaded shank of a reamer inserted in said bore whereby said reamer may be moved through said bore on rotation thereof.
7. A device for reaming a bushing in the end of a connecting rod of an automobile engine having in combination, a member having at one end jaws adapted to be clamped to the connecting rod shank adjacent the end having the bore to be reamed, a member at the other end of said first mentioned member movable longitudinally and laterally of the connecting rod, said last mentioned member having an aperture through one end, a member internally threaded to embrace the threaded shank of a reamer and receivable and automatically centerable in said aperture and adapted to receive and embrace the threaded shank of said reamer when the same is disposed in the bore of said connecting rod and centered therein, said centering means thus acting to align said aperture axially with said bore.

In testimony whereof I affix my signature.
